UNITED STATES PATENT OFFICE

ALPHA H. METCALF, OF ATTLEBORO, MASSACHUSETTS, ASSIGNOR TO THE BAER & WILDE COMPANY, OF ATTLEBORO, MASSACHUSETTS

DESIGN FOR A CUFF BUTTON

Application filed February 18, 1932. Serial No. 42,917. Term of patent 14 years.

To all whom it may concern:

Be it known that I, ALPHA H. METCALF, a citizen of the United States, a resident of Attleboro, in the county of Bristol and State of Massachusetts, have invented a new, original, and ornamental Design for a Cuff Button, of which the following is a specification, reference being had to the accompanying drawings, forming part thereof.

I claim:

The ornamental design for a cuff button, as shown.

In testimony whereof I have signed my name to this specification.

ALPHA H. METCALF.
